US00D738891S

(12) **United States Design Patent**
Bae et al.(10) **Patent No.:** **US D738,891 S**
(45) **Date of Patent:** **** Sep. 15, 2015**(54) **DISPLAY SCREEN OR PORTION THEREOF
WITH GRAPHICAL USER INTERFACE**D607,002 S 12/2009 Jonasson et al.
D619,594 S 7/2010 Jonasson et al.
D624,931 S 10/2010 Agnetta et al.
D657,369 S 4/2012 Hecht et al.
D660,313 S 5/2012 Williams et al.
D660,861 S 5/2012 Lee et al.(71) Applicant: **Samsung Electronics Co., Ltd.,**
Suwon-si (KR)(72) Inventors: **Hyo-Jin Bae**, Seoul (KR); **Yong-Chae
Jung**, Seoul (KR); **Min-Hae Kim**, Seoul
(KR)(73) Assignee: **Samsung Electronics Co., Ltd.,**
Suwon-si (KR)(**) Term: **15 Years**(21) Appl. No.: **29/531,395**(22) Filed: **Jun. 25, 2015****Related U.S. Application Data**(63) Continuation of application No. 29/457,125, filed on
Jun. 7, 2013.**(30) Foreign Application Priority Data**

Feb. 23, 2013 (KR) 30-2013-0009592

(51) **LOC (10) Cl.** ..... **14-04**(52) **U.S. Cl.**USPC ..... **D14/485**CPC ..... **G06F 3/04817** (2013.01)**(58) Field of Classification Search**

USPC D14/485-495; 715/700-867, 973-977

CPC G06F 3/0481-3/0486

See application file for complete search history.
